UNITED STATES PATENT OFFICE.

OTTO KROMER AND CHARLES OHLEMACHER, OF SANDUSKY, OHIO.

IMPROVEMENT IN BELT-CLASPS.

Specification forming part of Letters Patent No. **59,914**, dated November 20, 1866.

To all whom it may concern:

Be it known that we, OTTO KROMER and CHARLES OHLEMACHER, of Sandusky, in the county of Erie and State of Ohio, have invented certain new and useful Improvements in Machine-Belt Clasps; and we do hereby declare that the following is a full and complete description of the same, reference being had to the accompanying drawings, making a part of this specification, in which—

Figure 1 is an outside view of the belt when clasped; Fig. 2, an edge view of the same; Fig. 3, a view of the clasp.

Like letters of reference refer to like parts in the several views.

Fig. 3 is the clasp, which may be made of brass, iron, or any other suitable material. The clasp consists of two parts, A and B. A is a straight flat or round bar, and in length more or less, according to the width of the belt for which it is intended. C are arms or tongues projecting from the bar A, and which may be more or less in number, according to the width of the belt. These tongues terminate in a loop or eye, D, which may be either round or square, as may be thought best, and through which is passed the rod B, for the purpose of coupling.

The manner of applying this buckle or clasp is as follows: The ends of the belt F, Fig. 1, being properly prepared by squaring, so

that they may fit evenly and smooth—the number of holes, also, being made for the reception of the tongues—are then brought together—that is, the two ends of the belt are laid flat upon each other, the tongues are then inserted through the holes, and the rod B then slipped through the loops or eyes. The belt, when thus coupled, is then spread out, and the ends thereby are brought closely and tightly together, as shown in Fig. 1. Fig. 2 shows the belt as it curves to the face of the pulley. The rods B are provided with a short point or spur, G, which is forced into the belt, and by this means are prevented from working out.

It will be seen that by this arrangement the belt is at all times secured equally from side to side, and that the tongues cannot come in contact with the face of the pulley, whereby they are caused to wear away and soon break.

What we claim as our improvement, and desire to secure by Letters Patent, is—

The bar or back A, the tongues C, rod or slide B, as arranged in combination with the belt F, for the purpose and in the manner as set forth.

OTTO KROMER.
CHAS. OHLEMACHER.
